DAVID GREGG, OF CALDWELL, NEW JERSEY, ASSIGNOR TO ECLIPSE AVIATION CORPORATION, OF EAST ORANGE, NEW JERSEY, A CORPORATION OF NEW JERSEY

SUPERCHARGER

Application filed March 13, 1931. Serial No. 522,491.

This invention relates to superchargers, and particularly to means for compressing the combustible mixture to be supplied to the combustion chambers of an internal combustion engine having a two-stroke cycle.

An object of the invention is to provide a novel construction for a supercharger of the type adapted to be driven from a rotatable member of an associated engine.

10 Another object of the invention is to provide a supercharger embodying a rotary valve mechanism of novel construction adapted to be rotated with a driven member mounted therein and rotatable about an axis eccentric 15 to the axis of rotation of said valve.

15 Another object of the invention is to provide a novel supercharger comprising a plurality of movable vanes or blades adapted to oscillate and at the same time rotate about an axis eccentric to the axis of rotation of the member on which the said vanes are mounted.

Another object is to provide a supercharger 20 in which the compressing action is produced by novel means operating to vary the volume of the compression chamber in accordance with the variation in the angle described by a rotating element of said novel means.

25 A further object is to provide a supercharger in which the compression chambers are so controlled as to be of constantly increasing volume during the intake period, and of constantly decreasing volume during the discharge period.

30 These and other objects of the invention will become apparent from inspection of the following specifications when read with reference to the accompanying drawing wherein is illustrated the preferred embodiment of the 35 invention. It is to be expressly understood, however, that the drawing is for the purpose of illustration only, and is not designed as a definition of the limits of the invention, 40 reference being had to the appended claims for this purpose.

In the drawing,

Fig. 1 is a transverse sectional view of a device embodying the invention; and

50 Fig. 2 is a sectional elevation view taken at

right angles to the viewpoint and along the line 2—2 of Fig. 1.

In the drawing, the invention is shown embodied in a cylindrical casing member 3 having oppositely disposed extensions 4 and 5, 55 the former constituting an entrance duct for the air or combustible mixture to be compressed in the casing 3 and then delivered to the intake manifold of the engine with which the exit passage 5 communicates. 60

It is to be understood, of course, that there may be interposed between the supercharger and the engine, or between the supercharger and the air intake duct, any suitable means for carbureting the combustible mixture 65 and otherwise conditioning the combustion supporting air to secure maximum efficiency of combustion in the combustion chambers of the engine, and that the location and operation of the same is not material to 70 the present invention which consists in the construction of a novel supercharger capable of application and use with any suitable arrangement of such devices.

Such a novel supercharger construction 75 comprises the provision of a cylindrical valve member 6 of the sleeve or tubular type having any desired number of pairs of longitudinally extending ports 7 and 7a each pair being cut in the cylindrical wall thereof at diametrically opposite locations thereon, and at angular distances corresponding to the number of ports, said sleeve member being adapted to closely fit the cylindrical surface of the chamber 3 and be rotated relatively thereto 80 by novel means now to be described.

The novel compressing means preferably takes the form of a plurality of curved blades or vanes 8 corresponding in number to the number of ports; and pivotally secured at 85 their outer ends to suitable pivots 9 extending from the inwardly turned ends of the member 6 and spaced equally about the periphery of said member between the successive ports 7 and 7a. The inner ends of the vanes 8 are 90 preferably pivotally connected by pins 10 journaled in ears 11 formed on shoes 12 which are slidably mounted about the end portions of the circumference of the driven drum or rotor 14, suitable annular grooves or tracks 100

13 being provided for this purpose in the end surfaces of the rotor 14, the latter being supported at either end thereof on bearing pins 18 secured in the supporting frame 19 eccentrically to the axis of rotation of sleeve 6, bearings 20 being provided to facilitate rotation of the member 14 about said bearing pins.

Any suitable driving means may be employed for imparting rotation to sleeve valve 6, but in the preferred form as illustrated, such driving means comprises the provision of a gear 23 rotatably supported on ball bearing 24 and secured to a flanged annular end 15 of plate 25 by suitable screws 26 the gear 23 being also drivably secured to the sleeve 6 by means of said screws 26, and being in mesh with a gear 27 which is in turn rotatable with the crankshaft or other rotatable member of 20 the associated engine.

As shown best in Fig. 2, the casing 5 is divided centrally by a partition 29 which thereby forms two exit ducts 30 and 31, each leading to the intake manifold or inlet port 25 of a cylinder (or group of cylinders firing at the same time). In the device illustrated there are four vanes and two sets of ports, compressing and timing the delivery of a charge for two cylinders or sets of cylinders.

For a three cylinder engine, (or engine with three sets of cylinders firing together—as, for example, a six cylinder two cycle engine with opposed cylinders) there would be six vanes, and three sets of spaced ports, and 35 three outlets.

Having thus identified the parts entering into the preferred embodiment of the invention herein illustrated, the operation will be seen to be as follows:

On rotation being imparted to the sleeve 6 through the intermediary of gears 23 and 27, and driving screws 26, the combustible charge will be admitted through each of the ports 7 during a portion of each revolution of the sleeve 6, the gearing being preferably timed so that admission occurs as the piston is in proper position to insure properly timed delivery of the charge to the combustion chambers of the cylinder. Following the admission of the charge through the port 7, the oscillating action of the vanes 15 (as their shoes 12 slide at variable speeds along tracks 13) compresses the charge and, after half a revolution, forces it through the port 7 into the chamber 31, from which chamber it leads to the proper combustion point. Continued rotation of sleeve 6 eccentrically to the rotor 14 will bring the port 7a into registry with the intake passage 4, and at the same time will 60 bring the opposite port 7a into registry with outlet chamber 30, whereupon a similarly compressed charge will be delivered thereto.

Due to the spiral and rearwardly extending disposition of the vanes 15 relatively to 65 the direction of rotation of sleeve 6, the di-

rection of the gases toward the outlet chambers is facilitated and greater efficiency of operation thereby assured. Moreover, the novel construction of the vanes 8 whereby they are pivotally mounted at their ends to produce a constantly changing angularity with respect to the rotor 14, in conjunction with the disposition of the ports 7 and 7a, operates to produce a proper timing of the compressing action with respect to the volume of the associated chambers.

The constantly changing angularity of the vanes causes shoes 12 to move at angular speeds which vary in accordance with the change in the angle described by the shoes while rotating. A corresponding variation occurs in the volume of each chamber due to the disposition of the parts as above suggested, the relation of ports to vanes being such that each chamber is of constantly increasing volume during the entire period of communication between the intake duct and the valve port for the corresponding chamber, and is of constantly decreasing volume during the period of communication between the said port and the fluid discharge duct. Thus there is obtained a perfect synchronization between volume change and pressure change which insures maximum efficiency in 95 operation.

It will be understood, however, that various changes may be made in the form, details of construction, arrangement of parts and the uses to which they are applied.

What is claimed is:

1. In a device of the class described, a tubular member, a rotatable shoe associated therewith, a vane pivotally connected at one end to said tubular member and at the other end to said shoe, means for mounting said shoe for rotation about an axis eccentric to the axis of said tubular member, and means for rotating said shoe about said eccentric axis at a non-uniform speed in response to uniform rotation of said tubular member, said means comprising an annular track along which said shoe may slide with a speed which varies periodically in accordance with the angularity of said vane with respect to said shoe and tubular member, said shoe having a projection thereon forming with the track a tortuous sealing passageway.

2. In a rotary compressor, a housing having a fluid entrance duct and a fluid exit duct, and means for establishing periodic communication therebetween comprising a tubular valve member having a port formed in the cylindrical wall thereof, a rotor for actuating said valve member to cause said port to register alternately with said entrance and exit ducts, and means mounted within said valve member to form a chamber in which the fluid entering said valve member through said port is compressed prior to delivery to said exit duct, said last named means com-

prising a shoe slidably mounted for rotation with said valve member, and a vane pivotally connecting said shoe and valve member, said shoe forming a seal between the housing and tubular member and having an inturned flange nested with the rotor to form a tortuous passage therebetween.

3. In a rotary compressor, a cylindrical housing having end walls, a tubular valve member having closed ends rotatably mounted therein, a rotor eccentrically mounted in the valve member, vanes pivotally connected to the valve member, said rotor having annular guideways in its end faces arranged adjacent the end walls of the housing, shoes slidably positioned in the guideways flush with the end walls of both rotor and valve, and said shoes having pivotal connections with the vanes.

20 4. In a rotary compressor, a cylindrical housing having end walls, a tubular valve member having closed ends rotatably mounted therein, a rotor eccentrically mounted in the valve member, vanes pivotally connected to the valve member, said rotor having annular guideways of L-shaped cross section in its end faces arranged adjacent the end walls of the housing, shoes of L-shaped cross section slidably positioned in the guideways flush with the end walls of both rotor and valve, and said shoes having pivotal connections with the vanes.

5. In a rotary compressor, a cylindrical housing having end walls, a tubular valve member having closed end walls rotatably mounted therein, said end walls having their inner faces in alignment, a rotor eccentrically mounted in the valve member, vanes pivotally connected to the valve member and to the rotor by shoes relatively movable in their angular relation to the rotor, said shoes having a plane outer face adapted to contact the inner end walls of both the housing and tubular member for preventing leakage there-

45 between.

6. In a rotary compressor, a cylindrical housing having end walls, a tubular valve member having closed end walls rotatably mounted therein, said end walls having their inner faces in alignment, a rotor eccentrically mounted in the valve member, vanes pivotally connected to the valve member and to

the rotor by shoes relatively movable in their angular relation to the rotor, said shoes having a plane outer face adapted to contact the inner end walls of both the housing and tubular member for preventing leakage there- 70 between, and each of said shoes having an inwardly extending flange slidably fitted in a corresponding annular groove in the end face of the rotor.

7. In a rotary fluid compressor having a cylindrical housing, a tubular valve member rotatably mounted therein, a rotor eccentrically mounted in the member, hinged vanes connecting the rotor and member forming therewith sets of variable volume compartments, the connection of the vanes with the rotor including shoes having arcuate projections coacting with an annular groove in the rotor end face, said vanes being angularly movable with respect to the rotor, an inlet for the compressor, a plurality of outlets, conduits corresponding in number to the number of compartment sets, and means for delivering fluid from the compressor to the outlets selectively and in a regular recurring sequence. 75

8. In a rotary fluid compressor having a cylindrical housing, a tubular valve member rotatably mounted therein, a rotor eccentrically mounted in the member, hinged vanes connecting the rotor and member forming therewith sets of variable volume compartments, the connection of the vanes with the rotor including shoes having arcuate projections coacting with an annular groove in the rotor end face, said vanes being angularly movable with respect to the rotor, an inlet for the compressor, a plurality of outlets, conduits corresponding in number to the number of compartment sets, and means for delivering fluid from the compressor to the outlets selectively and in a regular recurring sequence. 80

9. In a rotary fluid compressor having a cylindrical housing, a tubular valve member rotatably mounted therein, a rotor eccentrically mounted in the member, hinged vanes connecting the rotor and member forming therewith sets of variable volume compartments, the connection of the vanes with the rotor including shoes having arcuate projections coacting with an annular groove in the rotor end face, said vanes being angularly movable with respect to the rotor, an inlet for the compressor, a plurality of outlets, conduits corresponding in number to the number of compartment sets, means for delivering fluid from the compressor to the outlets selectively and in a regular recurring sequence. 85

10. In a rotary fluid compressor having a cylindrical housing, a tubular valve member rotatably mounted therein, a rotor eccentrically mounted in the member, hinged vanes connecting the rotor and member forming therewith sets of variable volume compartments, the connection of the vanes with the rotor including shoes having arcuate projections coacting with an annular groove in the rotor end face, said vanes being angularly movable with respect to the rotor, an inlet for the compressor, a plurality of outlets, conduits corresponding in number to the number of compartment sets, means for delivering fluid from the compressor to the outlets selectively and in a regular recurring sequence. 90

11. In a rotary fluid compressor having a cylindrical housing, a tubular valve member rotatably mounted therein, a rotor eccentrically mounted in the member, hinged vanes connecting the rotor and member forming therewith sets of variable volume compartments, the connection of the vanes with the rotor including shoes having arcuate projections coacting with an annular groove in the rotor end face, said vanes being angularly movable with respect to the rotor, an inlet for the compressor, a plurality of outlets, conduits corresponding in number to the number of compartment sets, means for delivering fluid from the compressor to the outlets selectively and in a regular recurring sequence. 95

12. In a rotary fluid compressor having a cylindrical housing, a tubular valve member rotatably mounted therein, a rotor eccentrically mounted in the member, hinged vanes connecting the rotor and member forming therewith sets of variable volume compartments, the connection of the vanes with the rotor including shoes having arcuate projections coacting with an annular groove in the rotor end face, said vanes being angularly movable with respect to the rotor, an inlet for the compressor, a plurality of outlets, conduits corresponding in number to the number of compartment sets, means for delivering fluid from the compressor to the outlets selectively and in a regular recurring sequence. 100

13. In a rotary fluid compressor having a cylindrical housing, a tubular valve member rotatably mounted therein, a rotor eccentrically mounted in the member, hinged vanes connecting the rotor and member forming therewith sets of variable volume compartments, the connection of the vanes with the rotor including shoes having arcuate projections coacting with an annular groove in the rotor end face, said vanes being angularly movable with respect to the rotor, an inlet for the compressor, a plurality of outlets, conduits corresponding in number to the number of compartment sets, means for delivering fluid from the compressor to the outlets selectively and in a regular recurring sequence. 105

14. In a rotary fluid compressor having a cylindrical housing, a tubular valve member rotatably mounted therein, a rotor eccentrically mounted in the member, hinged vanes connecting the rotor and member forming therewith sets of variable volume compartments, the connection of the vanes with the rotor including shoes having arcuate projections coacting with an annular groove in the rotor end face, said vanes being angularly movable with respect to the rotor, an inlet for the compressor, a plurality of outlets, conduits corresponding in number to the number of compartment sets, means for delivering fluid from the compressor to the outlets selectively and in a regular recurring sequence. 110

15. In a rotary fluid compressor having a cylindrical housing, a tubular valve member rotatably mounted therein, a rotor eccentrically mounted in the member, hinged vanes connecting the rotor and member forming therewith sets of variable volume compartments, the connection of the vanes with the rotor including shoes having arcuate projections coacting with an annular groove in the rotor end face, said vanes being angularly movable with respect to the rotor, an inlet for the compressor, a plurality of outlets, conduits corresponding in number to the number of compartment sets, means for delivering fluid from the compressor to the outlets selectively and in a regular recurring sequence. 115
